US00D625043S

(12) **United States Design Patent**
Tessnow et al.

(10) **Patent No.:** US D625,043 S
(45) **Date of Patent:** ** Oct. 5, 2010

(54) **LAMP OPTIC**

(75) Inventors: **Thomas Tessnow**, Weare, NH (US);
David Hulick, New Boston, NH (US);
Jack Nudd, Lempster, NH (US)

(73) Assignee: **OSRAM SYLVANIA Inc.**, Danvers,
MA (US)

(**) Term: **14 Years**

(21) Appl. No.: **29/349,054**

(22) Filed: **Mar. 4, 2010**

(57) **CLAIM**

The ornamental design for a lamp optic, as shown and
described.

DESCRIPTION

FIG. 1 is a perspective view of a lamp optic as seen from the
top, front side, wherein the broken line disclosure is for envi-
ronmental purposes only and does not form a part of the
claimed design;

FIG. 2 is a top plan view of a lamp optic;

FIG. 3 is a front elevational view of a lamp optic being
rotationally symmetric except for the unclaimed broken line
disclosure; and,

FIG. 4 is a bottom plan view of a lamp optic.
